United States Patent Office

Des. 227,737
Patented July 17, 1973

227,737

PULL

Lee Richard Chasen, Port Chester, N.Y., assignor to
Coats & Clark, Inc., New York, N.Y.

Filed Dec. 22, 1971, Ser. No. 211,161

Term of patent 14 years

Int. Cl. D8—06

U.S. Cl. D8—147

Fig. 1.

Fig. 2.

Fig. 3.

Fig. 4.

FIG. 1 is a front view of the pull;
FIG. 2 is a back view of the pull shown in FIG. 1;
FIG. 3 is a top view of the pull shown in FIG. 1 (the
bottom view being the same);
FIG. 4 is a side view of the pull shown in FIG. 1 (both
side views being the same).
I claim:
The ornamental design for a pull, as shown and de-
scribed.
